UNITED STATES PATENT OFFICE.

FRANK MCINTYRE, OF NEW YORK, N. Y., ASSIGNOR TO THEODORE H. JOSEPH AND JAMES J. EHRENREICH, OF NEW YORK, N. Y.

ELECTRIC-LAMP-SHADE HOLDER.

No. 822,219.

Specification of Letters Patent.

Patented May 29, 1906.

Application filed April 4, 1902. Serial No. 101,846.

To all whom it may concern:

Be it known that I, FRANK MCINTYRE, a citizen of the United States, and a resident of New York, in the county of New York and State of New York, have invented certain new and useful Improvements in Electric-Lamp-Shade Holders, of which the following is a specification.

The standard lamp-socket, and practically all lamp-sockets for incandescent lamps, have a cylindrical recess on the outside of the same by which two shoulders are formed.

My invention relates to a spring shade-holder adapted to be clamped around the socket, so that a portion of the holder bears upon one shoulder and a portion upon the other shoulder, thereby preventing any possibility of the holder slipping off from the socket and preventing also any rattling or any motion of the shade, the shade-holder, and the socket relatively to one another.

The invention is described in all its details by reference to the accompanying drawings.

Figure 1 is an elevation of my preferred form of shade-holder shown in elevation in combination with a lamp-socket and lamp-shade. Fig. 2 is a view of a socket, shade-holder, and lamp. It is an elevation with the shade omitted and with the shade-holder applied to the socket. Fig. 3 is a plan of a modified form of shade-holder, being modified by the addition of another element. Fig. 4 is an outline of a portion of the shade-holder shown in Fig. 3 in order to exhibit a side view of a detail of construction. Fig. 5 is a plan of a modified shade-holder applied to a kind of shade usually made of metal. Fig. 6 is a plan of a shade-holder constructed on the same principle, but made in sections. Fig. 7 is a sectional view of a portion of a shade-holder and shade, the other parts being broken away and omitted. Fig. 8 is a perspective view of a complete ring, of which only a portion is seen in Fig. 7. Fig. 9 is a side view of the clips on the ends of the wire. Fig. 10 is a side view of the clips on the ends of the wire.

The socket is represented at 1 and is shown provided with the usual recess 2, having the upper shoulder 3 and the lower shoulder 4, these shoulders forming the sides of the recess 2 and being annular.

It is the object of my invention to provide a clamp shade-holder that may have one of its parts pressing against the shoulder 3 and with one of its parts pressing against the

shoulder 4 and yet to be independent of nuts and screws and to be applied easily by the mere process of operating a clamp.

A strip of metal, preferably a spring-wire whose degree of stiffness and elasticity may be easily determined by a mechanic, is bent into such a shape that one portion becomes clamped to the shade and the other portion to the socket within the recess and so that a portion of the wire runs parallel at intervals and against one of the shoulders 3 or 4 and so that other portions of the same wire bear against the other shoulder.

More particularly the wire is bent into loops 5. The loops 5 are bent into small loops 6 at the ends to form clips for extending around and under the lip 7 of the shade for the purpose of supporting the latter. The arms of the loops should not touch each other when on the socket. The space between them is shown, for example, at 8 in Fig. 75. By having this space provided there is more spring action for the loops, and as a result it is immaterial whether the shades are all of the same size or not as to the diameter of the lip portion. These shade-holders 80 may be applied effectively to shades having lips of different diameters.

Portions 9 of the loops 5 are bent so as to be in planes parallel to the axis of the socket, assuming that the holder is on the socket, 85 and these portions 9, consisting of wire extending up and down, reach such a distance that their lengths are equal to the height of the recess 2. The bend of the wire between the loops 5 and the portions 9 of said loops 90 form an angular portion 10, which presses upon one of the shoulders 3 or 4, it is immaterial which. In Fig. 1 the construction is such that this angular portion presses upon the lower shoulder 4, whereas in Fig. 2 the 95 angular portions 10 press upon the upper shoulder 3.

The wire as to its remaining portion is not bent into loops, except that the ends are bent downward and backward upon themselves to 100 form clips 11 substantially like those numbered 6.

That portion of the wire that is not bent into loops is bent into circular portions 12, which are adapted to press against one of the shoulders 3 and 4 and therefore are curved into arcs.

The end portions of the wire between the

clips 11 and these circular portions 12 are numbered 13. On one of them is pivoted a clamp 14, consisting of a hook adapted to clamp over one of the end portions 13.

5 There may be clamps 14' on more or less of the other loops 5. They are all shown in an open position in Fig. 5. The clamps 14' may be omitted, if desired. They might all be put on probably for holding shades in railway-trains where the vibration is great.

It comes within my invention to divide the wire into sections and to clamp these sections together, so that the result is practically a shade-holder formed from a single piece of 15 wire. This is illustrated in Fig. 6. When the halves there shown, A and B, are applied around the socket, the clamps 14 will when locked secure the holder to the socket.

In order to still further increase the friction 20 between the holder and the socket, there may be a metal ring 15 fastened to the circular portions 12 by means of hooks 16, consisting of portions of the ring 15, made by parallel cuts into said ring and then bent to form 25 hooks 16 just outside of the periphery of the ring 15 and partly surrounding the arc-shaped portions 12, which therefore lie between and against the ring 15 and the hooks 16. The height of the ring 15 is equal to the distance 30 between the shoulders 3 and 4, so that when the end portions 13 are clamped together there can be no doubt about the rigidity between the socket and the lamp-holder.

Some dealers prefer that the raw edge 17 of 5 the shade should be concealed or finished off with metal for the sake of appearance. My invention permits this result to be accomplished. To this end I provide an angular ring C, having a cylindrical portion 19 40 hanging from the top edge 17 and having a plane annular portion 20 covering the raw edge 17. The clip portions 6 of the shade-holder pass through notches 21 in the cylindrical portion 19 of the angular ring, and thus 45 said ring is retained in position.

The complete operation is as follows: The shade-holder is applied by hand with the clip 6 under the lip of the shade 22 and with the circular portions 12 against one of the shoulders 3 or 4, and then the ends 13 are pressed together and the clamp closed. This is the whole operation, and it is similar, only reversed, when the shade is to be removed from the holder and the holder from the socket or 55 the shade may be removed and the holder left on the socket.

When the plate 15 or ring of sheet-brass is employed, the wire need not be bent to form the vertical portions 9, but only the circular 60 portions 12 on the loop portions 5. Even all the clamps may be omitted from the device, provided only that the wire has the proper stiffness to clamp the socket by its own strength.

65 The slant on which the loops 5 extend

downward determines the amount of automatic adjustment of the holder with respect to variation in the size of the shade under the lip. Decreasing the slant decreases the adjustment, but increases the rigidity with 70 which the shade is held.

These shade-holders may be applied to sockets of all description, whether the shell is made of brass, porcelain, mica, or other material. For sockets of special design in 75 which the width of the annular recess varies the portions 9 can be made of lengths suited to fit same.

I claim as my invention—

1. The combination with a lamp-shade 80 which has an outwardly-projecting lip, and a lamp-socket having annular projections spaced apart, to form a cylindrical recess thereon, of a wire having circular portions pressing against one of said projections, loop 85 portions pressing against the other projection, said loop portions being bent outward and downward, and then inward to form clips for passing under the lip of said shade, and a clamp for the end portions of the wire which 90 are bent outward and downward to form another clip for passing under the lip of the shade.

2. The combination with a lamp-shade, and a socket, annular projections thereon, a 95 spring-wire with bent portions, respectively arc-shaped and angular, and for bearing respectively upon said annular projections, clips formed from said wire for passing under the lip of the shade, and means for detachably clamping the ends of the wire together. 100

3. The combination with a shade which has a lip, and with a socket which has parallel annular projections, of a wire in a single piece with free ends, with bent portions for 105 pressing against the respective shoulders of the socket, and a latch pivoted to one free end and bent detachably around the other free end of said wire, the ends being bent to form clips for extending under the lip of the 110 shade.

4. The combination with a lamp-shade which has an outwardly-projecting lip, a lamp-socket having annular projections spaced apart, to form a cylindrical recess 115 thereon, of a wire having circular portions for pressing against one of said projections, loop portions for pressing against the other projection, said loop portions being extended outward and downward, clamps on the loop portions which extend beyond the clamps and are bent partly upon themselves for passing under the lip of the shade, the end portion of the wire being bent outward and downward and inward to form a clip for passing under 125 the lip of the shade, and means for clamping the ends of the wire together.

5. The combination with a lamp-shade, of a spring-wire with bent portions, respectively arc-shaped and angular, and for bearing re- 130

spectively upon different portions of a lamp-socket, clips formed from said wire for passing under the lip of a shade, means for detachably clamping the ends of the wire together, and a cover for the upper edge of the shade, said cover being retained by said clips.

6. The combination with a lamp-shade, a lip thereon, and with a socket having annular projections, of a spring-wire with bent portions, respectively arc-shaped and angular, and for bearing respectively upon said annular projections, clips formed from said wire for passing under said lip, means for detachably clasping the ends of the wire together, a cover for the upper edge of the shade, said cover being retained by said clips, said cover consisting of an angular ring whose one portion is adapted to cover the upper edge of the shade, and its other portion to hang down and around the lip of the shade.

7. The combination with a lamp-shade, a lip thereon, and a lamp-socket, of a holder having circular portions adapted to be clamped upon said socket, and having loop portions bent to form clips for extending under said lip, and clamps applied to said loop portions.

8. The combination of a lamp-shade, a lip thereon, a socket, annular projections thereon, a piece of spring-wire having arc-shaped portions for bearing upon one of said annular projections, and having angular portions for pressing upon the other annular projection, and clips formed of said wire for passing under said lip.

9. The combination of a lamp-shade, a lip thereon, a socket, annular projections thereon, a single piece of spring-wire having arc-shaped portions for bearing upon one of the annular projections of said socket, and having angular portions for pressing upon another annular projection of said socket, clips formed of said wire for passing under said lip, and an angular ring covering the edge of the lip.

10. The combination of a shade, a lip thereon, a socket, projections thereon, clips for passing under the lip, an elastic wire having free ends, and means for clamping the ends together, one portion of the wire being adapted to press against a projection on the socket, and another portion being adapted to press upon another projection of the socket.

11. The combination with a lamp-socket having an annular recess, and with a shade, of a spring-wire having clips for holding the shade, and having portions thereof bent into and for bearing upon the surface of the recess.

12. The combination of a shade, a lamp-socket having an annular recess, a spring-wire having clips for holding the shade, and having portions thereof bent into and for bearing upon the surface of the recess, and

means for clamping the ends of the wire detachably together.

13. A shade-holder for a lamp-socket, consisting of a spring-wire having free ends, a succession of arc-shaped loops of the wire lying in a given cylindrical surface, radial looped portions bent at an angle to said surface, and then bent to form hooks lying in a given circle, and means for causing the arc-shaped loops to lie in a smaller cylindrical surface and said hooks in a smaller circle.

14. The combination with a lamp-shade and a socket, of a spring-wire with bent portions, one of which is arc-shaped around the axis of the socket and the other straight and parallel to said axis and both bearing upon said socket, clips formed from said wire for passing under the lip of the shade, and means for detachably clamping the ends of the wire together.

15. A shade-holder for a lamp-socket, consisting of arc-shaped portions, and arms having free ends, extending from and integral with said portions, said arms and portions forming a band, the ends of the band being turned outward to form ears, means for connecting said ears together and for disconnecting the ears from each other, the arms being provided at their ends with hooks to engage the attaching-flange of a shade, the band being for gripping the socket, and for drawing the hooks radially toward each other with pressure upon said flange, when the said ears are drawn together and connected by said means.

16. A shade holder, consisting of a spring adapted to be clamped upon a lamp-socket, and having arms extending therefrom and free at their outer ends, where they terminate in hooks, each having only a single curvature for gripping the lip of a shade, and for pressing radially inward upon the shade, and a pivotally-hinged clamp for connecting the ends of said spring.

17. A shade-holder consisting of arc-shaped portions, a plurality of integral uniform arms extending therefrom, said portions and arms forming the attaching-band of a holder, and said portions being formed to bear upon the sides of a groove on the socket of a lamp, and the ends of the band being turned outward to form ears, and the arms being provided with hooks at their ends to engage the attaching-flange of a shade, and means engaging said ears, whereby the said band is caused to grip the said socket and the hooks are simultaneously closed radially inward upon the attaching-flange of the shade.

18. A shade-holder of the character described, comprising a spring having a plurality of uniform arms extending therefrom, and provided with surfaces for bearing upon the sides of a groove on the lamp-socket, and the ends of said spring being turned outward

to form ears, and the arms being provided at their ends with hooks to press radially inward upon the attaching-flange of a shade, and a clamp engaging the ears of the spring, whereby the spring is caused to grip a socket-shell, and the hooks are simultaneously closed upon the attaching-flange of a shade.

19. The combination of a lamp-socket, a spring forming the attaching-band of a shade-holder, one of the above-named elements having a groove and the other having bearing-surfaces for bearing upon the surface of said groove, said spring having a plurality of arms integral therewith, said spring being bent outward at its ends to form ears, and said arms terminating in hooks, each hook having only a single curvature, to engage the attaching-flange of a shade, and a clamp en-

gaging the ears of said spring which is caused to grip said socket, the hooks being simultaneously closed upon the attaching-flange of said shade by the action of said clamp.

20. A holder for a lamp-shade consisting of a spring, hook-arms, and terminal ears all in a single piece for detachably supporting a shade, and means for clamping the ears detachably together, and for pressing the hooks against the shade in a radially-inward direction.

Signed at New York, in the county and State of New York, this 29th day of March, A. D. 1902.
